UNITED STATES PATENT OFFICE

164,590

TIMED AUTOMATIC PET FEEDER

Frederick J. Mulhern, Waterford, N. Y.

Application June 22, 1950, Serial No. 10,697

Term of patent 14 years

(Cl. D12—2)

To all whom it may concern:

Be it known that I, Frederick J. Mulhern, a citizen of the United States, residing at Waterford, in the county of Saratoga and State of New York, have invented a new, original, and ornamental Design for a Timed Automatic Pet Feeder, of which the following is a specification, reference being had to the accompanying drawing, forming part thereof.

Figure 1 is a perspective view of a timed automatic pet feeder, showing my new design.

Figure 2 is a plan view of the feeder.

Figure 3 is a side view of the feeder.

The dominant features of the design reside in the portions shown in full lines.

I claim:

The ornamental design for a timed automatic pet feeder, as shown and described.

FREDERICK J. MULHERN.
